Primary Examiner — Ieisha N Price(74) *Attorney, Agent, or Firm* — Ying-Ting Chen; Law Office of Michael Chen(57) **CLAIM**

The ornamental design for a vehicle bracket, as shown and described.

DESCRIPTION

FIG. 1 is a perspective view of a vehicle bracket showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of a vehicle bracket in a different configuration.

The broken lines shown on the drawings depict portions of the vehicle bracket that form no part of the claimed design.
